UNITED STATES PATENT OFFICE.

LYMAN R. ROBERTS, OF RUTHERFORD, NEW JERSEY, ASSIGNOR TO UNDERWOOD
TYPEWRITER COMPANY, OF NEW YORK, N. Y., A CORPORATION OF DELAWARE.

AUTOMATIC TYPE-WRITER OPERATOR.

1,252,845

Specification of Letters Patent.

Patented Jan. 8, 1918.

Application filed June 7, 1916. Serial No. 102,114.

To all whom it may concern:

Be it known that I, LYMAN R. ROBERTS, a citizen of the United States, residing in Rutherford, in the county of Bergen and 5 State of New Jersey, have invented certain new and useful Improvements in Automatic Type-Writer Operators, of which the following is a specification.

This invention relates to an improvement 10 in typewriter operators and more especially to the class in which all of the functions of the typewriter can be taken care of automatically, whereby not only one but a dozen machines can be looked after by a single 15 operative, it being merely necessary that the blank paper be supplied thereto in stacks and the typewritten matter removed as accumulated.

This application contains matter divided 20 out of my application Serial No. 806,408 filed December 13, 1913.

An object of this invention is to produce a machine which will be simple in construction, compact in its arrangement, and with 25 the operating parts secluded as much as possible and retired from an exposed position.

The machine is of the general type in which the parts are operated by pneumatic actuators, which are controlled by one, or 30 more master members passing over tracker boards. In this case two tracker boards are shown, one for writing the body of the matter, such as a letter, and the other for writing inserts, such as a new name and address 35 for each letter. Of course, the inserted matter may also be placed, if desired, even in the midst of the letter, under the control from the second tracker board. The master members are shown of the perforated type, 40 so that when they pass by their tracker boards, they bring perforations successively into register with apertures in the tracker boards in order to admit air to individual controllers, each of which governs the action 45 of a pneumatic actuator. This actuator is connected by mechanical means to the particular part of the typewriter which it is to operate. By this means a successive series of actions of the typewriter may be produced according to any predetermined plan 50 which is governed by the perforations in the master member.

As stated above, in the present case one master member controls the body of the

written matter and the other master member 55 controls the inserts. It is therefore essential to shift the control of the operator from one master member to the other. This is controlled by special perforations in each master member, so that they bring into action 60 at proper times, shifting mechanism which enables first one master member to be in ascendancy and then the other. In the present instance, where one master member controls the body of the writing, it is desirable 65 to make the same of an endless sheet, so that it can repeat over and over again by passing continually over the tracker board with interruptions mainly for the purpose of allowing the other master member to control 70 the operation of the machine. The other master member in this case is, in fact, a series of individual master members shown in the form of a series of cards perforated to correspond to different inserts, 75 which, in the present case, are different names and addresses.

The paper to be written on is supplied to the machine in packs and picked up sheet by sheet at the proper time under the control of one of the master members, by a pneumo-mechanical mechanism, which drops the sheets one by one to the platen on the typewriter as the carriage reaches the end of its return movement. The sheet so dropped is fed beyond the heading thereof, to a point to receive the first line of typewriting, while the previous sheet, which has been completely written on, is fed out and received in a suitable receptacle.

Among the important improvements in the present case, is the means for rotating the platen when a new sheet is fed thereto as mentioned above, to bring the first line for writing to the printing point and to remove the completely written sheet from the platen. This is accomplished by a special drive for the platen from a motor, whose connection to the motor is normally interrupted and made continuous by a clutch 80 when a proper opening in one of the master members comes into register with an aperture in the corresponding tracker board. When closed the clutch is automatically locked in its closed condition so as to continuously drive the platen any predetermined amount. At the same time that the clutch is closed, a valve is connected to be

traversed from the driving mechanism of the platen until it comes into engagement with an adjustable stop, whereby it is opened. The opening of the valve excites a pneumatic actuator, which actuator releases the locking means for the clutch, thereby interrupting the drive to the platen, and also disconnects the valve from the traversing means therefor, so that it can be returned by 10 a spring to its normal position. The adjustment of the stop determines the extent of travel of the valve, and hence, the extent of rotation of the platen, which is proportionate thereto, whereby the platen may 15 be rotated any desired number of line spaces.

The platen may also be rotated in line-space direction by the carriage-returning mechanism.

20 Other features and advantages will hereinafter appear.

In the accompanying drawings:

Figure 1 is a general view in side elevation of the machine as a whole, with parts 25 omitted for the sake of simplicity, and showing, in dotted lines, the path of travel of a completely typewritten sheet in leaving the platen.

Fig. 2 is a skeleton view in side elevation, 30 showing the means for silencing the feed for both tracker boards when the platen is being rotated.

Fig. 3 is a perspective view showing part of the platen rotating means.

35 Fig. 4 is a skeleton perspective view, showing the mechanism for controlling the termination of the extent of drive of the platen in bringing a new sheet to the writing point.

40 Fig. 5 is a horizontal view in section, on the line 5-5 of Fig. 1, of the lower part of the machine, showing the motor drive and some of the connections to the lower tracker board.

45 Fig. 6 is a vertical section through the master-card feeding and substituting mechanism.

Fig. 7 is a detail section through one of the pneumatic actuators and the control 50 thereof.

Fig. 8 is a detail view of the platen-rotating and sheet-feeding drive.

Fig. 9 is a rear view in elevation of the platen-rotating mechanism which is used 55 when the sheet is first fed to the platen to bring the initial line of printing to the printing point, that is, the feeding mechanism which rotates the platen in passing the heading on the sheet to be typewritten 60 and in removing a written sheet from the platen.

Fig. 10 is a detail perspective view of the mechanism for controlling the extent of feed or rotation of the platen.

65 Fig. 11 is a skeleton perspective view

showing the two trackers and the branch connections of the tubing thereto, whereby either tracker may control much of the actuating mechanism, such as the actuators for the keys, which must be commonly operated under the control of both the trackers. 70

An operator 1 actuates all of the parts of a typewriter 2 essential to a complete typewriting action.

Considering briefly the parts of the typewriter, which is shown in the present instance to be an Underwood although any other machine might be used, character keys 3 (Fig. 1) operate levers 4 to rock bell cranks 5, so as to swing type-bars 6 up rearwardly against the front side of a platen 7 mounted to rotate on a carriage 8, which travels on ways on the frame of the typewriter, under the control of an escapement mechanism indicated in general at 9. This escapement mechanism includes a rack bar 10, pivotally mounted on the frame of the carriage 8, so as to swing into and out of engagement with a pinion 11 connected to rotate with an escapement wheel 12, which is controlled by a pair of dogs 13 actuated by a universal frame 14, which is operated at the actuation of any of the keys, by heels 15 provided on all of the type-bars. The universal frame 14 is mounted for movement on a swinging frame 16. The frame 16 may be operated also by a space key 17, which forms also a part of the typewriting mechanism, and depresses a lever 18 to thrust up an arm 19 provided on the shift frame 16. The platen 7 has the usual line-space wheel which is engaged by the usual line-space mechanism including the line-space lever 21, which may be operated by hand or automatically in the manner to be described. 90

Having thus briefly described the more essential parts of the typewriter, a more elaborate and detailed description of the operator therefor may be taken up. The automatic operator for the typewriter has its motive source in an electric motor 22 (Fig. 1), which is provided with a shaft 23 having a worm 24 thereon meshing with a worm wheel 25 to drive the same, so as to drive a shaft 26 on which the worm wheel 25 is secured. The shaft 26 is provided with a pair of eccentrics 27 and 28 arranged in opposite phases on the shaft 26, so as to drive, by means of straps and eccentric rods 29, the two sections 30 and 31 of a bellows 32, the two sections 30 and 31 of a bellows vacuum pump. One section will be filling while the other is exhausting, so that a common vacuum chamber 32 therefor will be always under a section so long as the motor 22 is driving. The suction or vacuum chamber 32 has connected thereto, a main pipe 33, which, by virtue of a feeder 34 and various laterals 35, is arranged to connect with the source of suction, the several pneu- 110 115 120 125 130

matic actuators for the different parts of the hereinafter mentioned vacuum chambers 48 of the mechanism.

Considering specifically the operation of 5 one of these pneumatic actuators, which will serve for all as they act substantially alike, it will be seen by reference to Fig. 7, that each actuator consists of a motor 36 in the form of a collapsible bellows, and a controller 37, which is connected to the motor by a pipe 38. Each controller 37 is connected by tubing 39 to either one or both of a pair of trackers or tracker boards 40 (Fig. 1) and 41 (Fig. 6), according to whether 10 the particular actuator to which the controller corresponds is to be controlled in its action by one or both of the trackers and their master members. That is to say, one of the trackers, take, for example, the tracker 40, is used to control the writing of the main portion or body of the matter to be typewritten, and the other, such as the tracker 41, is used to control the writing of the inserts, such as the different names and addresses placed 15 at the top of the several letters.

In the case of the tracker board 40, the master member which controls the same, is shown in the form of an endless perforated sheet 42 (Fig. 1), which may be passed repeatedly 20 in front of the tracker 40, as the matter which it controls, such as the body of the letter, is to be repeated over and over again in each new sheet of typewriting. In the case of the upper tracker 41, which controls 25 the writing of the inserts, the master member may, in fact, be several different master members shown in the form of individual perforated cards 43, which are successively brought into coöperation with the tracker 41 to successively control the action 30 thereof.

It is to be understood at this point that the control of the action of the operator 1 is alternately given over entirely first to one 35 tracker board and then to the other. That is to say, the upper tracker 41 will first control the writing of the address, then the control will be shifted to the lower tracker, when the body of the letter will be written; 40 after which, when a new sheet is placed on the typewriter, the control will again be shifted back to the upper tracker to write a new name and address for the new sheet, and so on.

Going back at this point to the particular 45 structure of each actuator and its controller, when one of the master members brings an opening therein into register with an aperture in its tracker board, the particular controller connected thereto by the tubing 39 will have air admitted in a chamber 44. This chamber is normally under a negative or sub-atmospheric pressure, as it is connected with the source of vacuum. This connection is obtained by having each of the

tubes or tubings 39 extend through a common suction or bleed chamber 45 (Fig. 1), connected by a lateral with the feeder 34, the portion of each tube within said bleed chamber 45 being provided with a bleed opening 46* of sufficient size to gradually exhaust the air from the corresponding chamber 44 in the accordant controller 37, but not fast enough to absorb the air admitted through the aligned apertures in the master sheet and the tracker in operation. It is thus evident that when air is admitted to the chamber 44 of any particular controller, it will fill the chamber 44 of the controller, raising a diaphragm 46 which forms the top of the chamber, and carrying with this diaphragm, a valve rod 47, which extends upwardly through an intermediate vacuum chamber 48 into an equalizing chamber 49. The chamber 48 is connected, as mentioned above, to the suction pump by the main pipe 33 and the feeder 34 and the laterals 35. This chamber 48 may be common, if desired, to a bank of controllers 37 or individual to each controller.

When the pressure of air admitted to the chamber 44 raises the diaphragm 46 and the valve rod 47 against the weight of the parts and the negative pressure in the vacuum chamber 48, it also raises a valve 50 secured to the valve rod 47. This valve 50 is duplex and first opens a passage 51, forming a means of communication between the vacuum chamber 48 and the equalizing chamber 49, and then closes a passage 52 between the equalizing chamber 49 and the outside atmosphere. That is to say, the valve 50 is double-ended and operates to alternately close and open the passages 51 and 52. When the valve 50 is raised, it connects the equalizing chamber 49 with the vacuum chamber 48, so that air is withdrawn from the equalizing chamber, and this will continue until the valve 50 closes the passage 52, when the air will not only be sucked out of the equalizing chamber 49, but, through the connecting pipe 38, will also be sucked out of the pneumatic bellows motor 36 forming the active part of the actuator. When the air is thus withdrawn from the interior of an actuator, the outside atmospheric pressure causes the same to collapse, so that any part connected to the moving side 53 thereof will be operated.

When the opening in the master sheet 120 passes out of register with the aperture in the tracker board which causes this action, the air will be cut off from the chamber 44, so that the air remaining therein will be sucked out through the bleed opening 46* until the pressure on both sides of the diaphragm 46 is balanced, causing the weight of the parts to drop the valve 50 to a position closing the passage 51 and opening the passage 52. The bellows motor 36 being cut off from the suc- 125 130

tion and opened up to atmospheric pressure, will expand and return to its normal condition with the aid of a spreading spring, not shown.

- 5 In the case of the actuators which operate the various keys of the typewriter, each one is provided with an arm 54 (Figs. 1, 4 and 6), which is connected by a link 55 to one arm of a bell crank 56. The other arm 57 of each bell crank 56 is provided with a pin 58, which overlies a hook 59 on a link 60 pivoted to the corresponding key of the typewriting mechanism. That is to say, each key is provided with a link 60 having hook 59 underlying one of the pins 58 on one of the bell cranks 56. The arms 57 of the bell cranks are of various lengths and arranged in echelon, so as to avoid one another and co-operate with their corresponding links 60.
- 10 15 20 25 30 35 40 45 50 55 60 65 70 75 80 85 90 95 100 105 110 115 120 125 130
- Having considered how the pneumatic actuator is constructed and acts, we may now go on to the description of the feeding mechanism for the master members, which control the action of all of the actuators, and how the shift is made from control by one to control by the other at the proper times.

The master sheet 42, which controls the writing of the main part or body of the type-written matter, such as the body of the letter, passes over a supporting feeding roller 61 (Fig. 5) and is warped across the face of the tracker 40 by means of an idle roller 62 (Fig. 1). The supporting roller 61 is provided with a gear 63, which may be driven at times by a gear 64 secured on a shaft 65, on which is also secured a roller 66. When the master sheet 42 and its tracker 40 are in control, the feeding roller 66 is dropped down to bind the master sheet 42 between its surface and the surface of the supporting roller 61. Under these conditions, the gear 64 will also mesh with the gear 63, so as to drive the same; hence the master sheet will be fed in the direction of the arrow shown in Fig. 1, past the tracker 40, bringing the several perforations therein successively into register with corresponding apertures in the tracker 40.

To drive the shaft 65 and thus the rollers 61 and 66, there is provided on the shaft 65, a gear 67 (Figs. 1 and 2), which meshes with a pinion 68 (Fig. 1) secured to a shaft 69 carrying a pulley 70, which is driven by an endless belt 71 from a pulley 72. The pulley 72 is secured to a shaft 73 on which is also secured a friction disk 74 driven by a friction roller 75 bearing against one surface on the disk 74. The friction roller 75 is secured to a shaft 76 driven by a pair of meshing bevel gears 77 and 78, from the cross shaft 26, which, as mentioned above, is driven from the motor 22.

The feeding mechanism for the upper master member is also driven from the shaft 73. For this purpose, there is provided on

this shaft, a second pulley 79 (Fig. 1), which is connected, by means of an endless belt 80, to drive a pulley 81 on a shaft 82. The shaft 82 also has secured thereon a pinion 83 meshing with the gear 84 secured on a shaft 85. Also secured on the shaft 85, there is provided a pinion 86, which when lowered (Fig. 6) is arranged to drive a pinion 87 secured on a shaft 88. The shaft 88 has secured thereon a sectional feeding roller 89, the sections of which extend through openings in a guide 90 to engage the upper master card 43 which happens to be in action. A similarly sectioned feeding roller 91 (Fig. 6) passes through openings in the guide 90 and co-operates with the opposite side of the master card 43 in action, so that when the shaft 88 is being driven, the card will be fed down by the co-operation of both the feeding rollers 89 and 91, they being connected to rotate in unison by pinions 92 and 93, secured, respectively, to the feeding roller 89 and the feeding roller 91. A bearing roller 94 corrugated so as to avoid obstructing the openings in the master card 43, holds the master card against the tracker 41, in order to obtain an airtight fit therebetween. This bearing roller is floatingly supported by a frame 95 (Fig. 6) pivotally mounted at 96, and engaged by a spring 97. As noted above, however, both master members, that is, the master card and the master sheet, are not in control at the same time. To regulate this change in control, the drive is completed to the feeding mechanism for one master member and interrupted to the feeding mechanism for the other master member, and vice versa. To accomplish this, the shaft 65 for the master sheet 42 is floatingly mounted by a frame including arms 97 (Figs. 1 and 4) pivotally supported on the shaft 69, so as to swing relatively thereto without disturbing the driving connection to the shaft 69. Likewise, the shaft 85 (Figs. 1 and 6) for the master sheet 43 is floatingly mounted by means of a frame including one or more arms 98 pivoted on the shaft 82, so as to swing relatively thereto without interrupting the connection between the gears 83 and 84. One of the arms 97 is provided with a camming socket 99, in which may rest a camming roller 100 secured to the lower end of a shifting lever 101. This shifting lever is pivoted, intermediate its ends, as at 102, and is provided at its upper end with a bearing-roller 103 co-operating with a cam socket 104 in one of the upper arms 98.

It will be seen that when the lever 101 is in the position shown in Figs. 1 and 4, the roller-bearing end of the arm 97 will be lowered, so as to permit the roller 66 to drive the master sheet 42, and also permit it to drive the supporting roller 61 through engagement of the gear 64 with the gear 63. 130

This same position of the lever 101, however, as shown in Fig. 1, causes the bearing-roller 103 to rest on the dwell portion above the cam socket 104 and thereby hold the gear 86 out of mesh with the gear 87, so that the drive to the feeding rollers 89, 91, is interrupted. On the other hand, when the lever 101 is shifted to the Fig. 6 position, the master card 43 will be in control as the gear 86 is dropped into mesh with the gear 87, completing the drive to the feeding rollers 89, 91, while the shaft 65 and the roller 66 are raised, interrupting the drive between the gear 64 and the gear 63.

In order to manipulate the shifting lever 101, a pair of pneumatic actuators 105 and 106 are provided which are adapted to shift the lever 101 in opposite directions. The actuator 105, which controls the bringing into play of the feeding mechanism for the master sheet 42, is controlled by a perforation in the particular master card 43 in action; while the actuator 106, which controls the bringing into play of the feeding mechanism for the master card 43 is controlled by a perforation in the master sheet 42. In other words, one master member controls the bringing into play of the other master member. As the actuators 105 and 106 are of the type described above and shown in Fig. 7, it is not necessary to re-describe them at this point. Sufficient to say that when the actuator 105 is brought into control by an aperture in the master card 43, it will assume the Fig. 1 position, whereby a link 107 will, by virtue of a hook or shoulder 108 (Fig. 6) thereon, draw the lever 101 to the Fig. 1 position, by engagement with a rod or lug 109 on the lever 101, the latter being yieldingly held in this position by a spring detent 101*, Fig. 1.

Now, when the master sheet 42 has finished its period of control, having completely written the body of a letter, after a new work-sheet has been supplied to the typewriter, then a perforation in the said master sheet 42 comes into register with a corresponding aperture in its tracker 40, so as to cause the pneumatic actuator 106 to collapse its bellows motor. This will bring about a condition in the actuator 106, whereby a thrust link 110 will be plunged forwardly, first causing a cam nose 111 thereon to engage a pin 112 on the link 107, disengaging the shoulder 108 from the lug 109, so as to free the lever 101 from the actuator 105 and its link 107. A further movement of the thrust link 110 causes a shoulder 113 thereon to engage the lug 109 and force the lever 101 from the Fig. 1 position to its Fig. 6 position, whereby the cam roller 103 will drop into the socket 104, permitting the arm 98 to lower the gear 86 into mesh with the gear 87, thereby completing the drive to the feeding rollers 89, 91, so as to feed the

master card 43 into position past its tracker 41. At the same time, the lower roller 100 and the lever 101 rock, by a camming action, the arm 97, so as to withdraw the gear 64 from its meshing position with the gear 63, 70 thereby interrupting the drive to the master sheet 42. When the master card thus started into control has been fed to the end of its capacity for control, and has finished writing a name and address, a perforation 75 therein comes into register with a corresponding aperture in its tracker 41, causing the actuator 105 to come into action. When this takes place, the actuator pulls the link 107 from the Fig. 6 position to a position 80 where the pin 112 engages the end of the nose 111, camming the latter upward, so as to disengage the shoulder 113 from the lug 109. A further movement of the link 107 under the pull of the actuator 105, causes 85 the shoulder 108 on this link to disengage the lug 109 and shift the lever 101.

It is advisable at times to throw out the feeding mechanisms for both the master card and the master sheet, as when it is necessary to stop the machine, or when the platen is rotated. In the last case, it would be inadvisable to have keys struck when the work-sheet is in motion. To accomplish this manually, as in stopping the 90 operation of the machine, there is provided a throw-out button 114 (Figs. 1, 2 and 4), which, when the machine is in action, has a groove 115 in register with a shifting bar 116, pivoted at 117. When, however, it is desired to disconnect the 100 drives for both the feeding mechanisms, the manual button is rotated from the Fig. 1 position to shift the bar 116 about its pivot 117 to draw on a link 118, so as to rock a bell crank 119. This bell crank is provided with an arm 120, having an offset 121 (Fig. 4), which underlies the arm 97 supporting the shaft 65 and the roller 66. The arm 120 of the bell crank 119 is also connected by a 110 link 122, to an arm 123 also having an offset underlying the shifting frame or arm 98, which shifts the gear 86 of the driving mechanism for the master card-feeding mechanism.

It will thus be seen that both the arms 97 and 98 will be swung with their gearing bearing end raised, so as to simultaneously interrupt the drive to both the feeding mechanisms. That is to say, when the button 114 is rotated it simultaneously interrupts the drive for both master members, so that the machine is silenced. This action is also effected, as will be explained presently, when the carriage is returning to begin a new line and when the platen is being rotated to either position the new work-sheet on the platen or to discharge a completed letter from the platen.

After one master card has completed its 130

work and shifted the control to the master sheet, then it must be removed from an effective position and a fresh card put in its place, so that a new name and address can be written on the next work-sheet fed to the platen, this is accomplished in a manner described in my herein mentioned patent.

While writing any matter with the typewriter, it is essential to return the typewriter carriage and to line-space the platen at the end of each line so as to enable the beginning of a new line. These features of this invention are described in my herein mentioned patent.

15 After a work-sheet has been completely written, as with the full name and address and body of the letter, this sheet must be removed from the platen and a fresh one put on in place thereof. To eject the finished sheet from the platen, the platen could be rotated by repeated operations of the line-space lever by the carriage-return mechanism. However, special means for rotating the platen is also provided which can accomplish the same purpose somewhat more quickly. For this purpose, the platen axle 215 extends beyond the frame of the carriage where it is provided with a sprocket 216 (Fig. 3) driven by a sprocket chain 217, which in turn is driven by a sprocket 218 on a shaft 219. The shaft 219 is provided with a gear 220 meshing with a barrel pinion 221 on a shaft 222, which is mounted to rotate on a fixed portion of the frame. The shaft 219 is mounted on the carriage so that it travels therewith and causes its gear 220 to mesh with the barrel pinion 221 when the carriage is at the end of its return movement. The barrel pinion is of considerable length so as to allow for the drive of the platen therefrom at a variety of positions of the carriage 8.

To drive the barrel pinion 221, the shaft 222 is provided with a bevel gear 223 (Fig. 9), which is driven by a bevel gear 224 on a shaft 225. This shaft 225 also has a bevel gear 226 driven by a bevel gear 227 loosely mounted on a shaft 228. The bevel gear 227, however, is normally connected in driven relation with the shaft 228 by a one-way clutch element 229 thereon meshing with a corresponding clutch element 230 splined on the shaft 228 (Fig. 8.) A spring 231 normally holds the clutch element 230 in mesh with the clutch element 229, so that rotation 55 of the shaft 228 in the direction of the arrow shown in Fig. 8, will be transmitted to the clutch element 229 and thus to the bevel gear 227. If, however, the shaft 228 rotates in a counter-direction, the clutch element 230 will 60 slip idly past the clutch element 229, without disturbing the gear 227 and the train of gearing to the platen. The shaft 228 is normally silent but has a sprocket wheel 232 loosely mounted thereon, by means of which

it may be driven. This sprocket wheel is 65 driven by a chain-and-sprocket connection 233 (Fig. 1), from the constantly-rotating motor 22 (Fig. 5).

To drive the shaft 228 from the sprocket wheel 232, there is provided on the sprocket wheel 232, a clutch element 234, into engagement with which may be shifted a clutch element 235 splined on the shaft 228 (Figs. 4 and 9.) The clutch element 235 is provided with an annular groove, into which extend pins on a clutch-shifter 236, which latter is normally held by a spring 237, in a position corresponding to the disengagement of the clutch element 235 with respect to the clutch element 234. The shifter 236, however, is provided with a follower roller 238, engaged by a cam 239 on a lever 240 pivoted at 241.

When it is necessary to rotate the platen, as in removing a completed sheet therefrom a perforation in the master sheet comes into register with an aperture in the tracker and excites to action a pneumatic actuator 242, so that the bellows motor thereof collapses to thrust forwardly a plunger 243. This plunger engages in a crotch 244 provided on the lever 240 and has a shoulder 245 to engage a part, forming with the lever 240 the crotch, so as to shift the lever 240 and cause the cam 239 to manipulate the shifter 236 against the tension of the spring 237 in order to bring 35 about an engagement of the clutch element 235 with the clutch element 234, thereby connecting the shaft 228 in driven relation with the sprocket wheel 232 which is constantly 40 rotating.

While the platen is rotating, it is essential to stop the movement of the master member in control, so the bar 116 is actuated to interrupt the drive to both master-member feeding mechanisms in the manner described above. For this purpose, the shifter 240, when actuated, also pulls on a link 250 to swing an arm 251 secured to a rock shaft 252, which is also provided with an arm 253 having an extension 254 engaging this bar 116, to rock the same to its disconnecting position shown in Fig. 2.

To insure the silencing of said master-member until said completed sheet has been removed from the platen, the plunger 243 is provided with a notch 246 which catches over a latch 247 on one face of the actuator 242, so that the bellows motor of the actuator is held in its collapsed position until the plunger 243 is raised out of engagement with the latch 247. This latter movement is permissible, inasmuch as the plunger 243 is pivotally mounted at 248 on a lug 249 carried by the moving side of the bellows motor of the actuator 242. By this arrangement, the clutch element 235 is held in engagement with the clutch element 234, so long as the plunger 243 is in locking engagement with

the latch 247. Under these conditions, the platen will be rotated through the train of gearing continuously, until the plunger 243 is raised, permitting the unclutching of the continuously-rotating sprocket 232 from the shaft 228. To accomplish this disconnection automatically, use is made of the actuator 203. For this purpose, a brach 255 (Fig. 4) of a tubing 202 which leads to the control of an actuator 203, is connected to a valve 256, which is normally closed but openable when the desired extent of rotation of the platen has been accomplished. When this valve is opened, it admits air in the usual way to the controller of the actuator 203, so that the bellows motor collapses and shoots forwardly a thrust link 204, which, carries a pin 257, arranged to engage one arm 258 (Figs. 1 and 4) of a bell crank lever, having a second arm 259 provided with a pin 260 underlying the plunger 243.

It will thus be seen that when the valve 256 is opened, it will raise the plunger 243, removing the notch 246 out of engagement with the latch 247, and removing the shoulder 245 out of engagement with the crotch 244, permitting the shifter 236 to return under the propulsion of the spring 237, to its disconnecting position, so that the shaft 228 will once more be silent, while the sprocket wheel 232 rotates idly. To open the valve 256, it is given a traveling movement coincident with the rotary movement of the platen and corresponding in extent to the extent of rotation of the platen desired. When the valve 256 completes its desired travel, it comes into engagement with a stop 261, which opens the valve and causes an operation of the actuator 203 as mentioned above. To traverse the valve 256, it is mounted on a carriage 262, which slides on ways or guide rods 263 of a rocking frame 264.

When the clutch element 235 is connected up to the clutch element 234 to drive the shaft 228, a pin 265 on the lever 240 engages an arm 266 on the rocking frame 264 to swing the same about its pivot against the tension of a spring 266^a and thereby bring a tooth or segment of a nut 267 (Fig. 10) into engagement with a bodily stationary but rotating screw 268 secured to the shaft 228 (Fig. 8).

It will thus be seen that so long as the shaft 228 is rotated to drive the platen, the screw 268 will be rotating to feed the carriage 262 carrying the valve 256 along on the ways 263, until a flange 269 on the gate 270 of the valve comes into engagement with the stop or trip 261, whereby this gate will be swung against the tension of a spring 271, from a normally closed position to an open position, admitting air to the controller of the actuator 203. When this occurs, as men-

tioned above, the plunger 243 is released, 65 opening the clutch elements 234, 235, thereby stopping the rotation of the shaft 228. The return movement of the lever 240 also permits the spring 266^a to swing the frame 264 back to its normal position, disconnecting 70 the tooth 267 from the screw 268, permitting the carriage 262 to be returned to its normal position, by a spring 272. When the valve 256 moves away from the stop 261, the spring 271 will automatically close the gate 75 270 thereof, permitting the actuator 203 to return to a normal condition. The stop 261 is adjustable so as to vary the extent of travel of the carriage 262 before the valve 256 is opened, and thus vary the period of 80 driving connection to the platen, whereby the number of line-spaces which the platen is rotated, may be varied.

To adjust the stop or trip 261, it is in the form of a nut having a screw-threaded engagement with a rod 273 on which it is mounted. The rod 273 is provided with a knurled handle 274 and the stop 261 is also knurled, so that they may be rotated relatively to each other, whereby the position of 90 the stop 261 along the rod 273 may be varied. It will thus be evident that the nearer the stop 261 is to the starting point in the travel of the valve 256, the sooner the drive to the platen will be interrupted.

In addition to rotating the platen to remove a completed work-sheet therefrom, the mechanism just described also rotates the platen to position a new clean work-sheet on the platen, so as to bring the point where it 100 is desired to have the first typewriting in register with the printing point of the typewriter. Before this new sheet, however, can be set to proper position on the platen, it must be supplied to the platen. For this purpose, there is provided automatic work-sheet feeding mechanism, which is described in my herein mentioned patent.

The blank work-sheets are deposited in a stack in an open-faced receptacle 275 from which they are automatically taken, one at a time, by a sheet lifter 283 and dropped into a chute 320 whence they are fed to the printing line as described in my herein mentioned patent.

In considering the operation of the device, it will be assumed that a letter has been completely written on a work-sheet on the platen and we are about to repeat this letter with a new name and address. The master sheet 42 (Fig. 1) is in control and the feeding mechanism therefor in operation, while the feeding mechanism for the master card is silent and a blank or solid portion of the master card in place is opposite to the 120 apertures in the tracker 41. As the master sheet 42 is fed past its tracker 40, it brings a perforation into register with a corre-

sponding aperture in the tracker 40, so as to enable a carriage-return movement. This is to insure the carriage being at the end of its return movement in a position to receive 5 a new work-sheet from the sheet-feeding mechanism.

When the carriage-return mechanism comes into play it automatically raises the gear 64 out of mesh with the gear 63 through 10 the intermediary of the bar 116, the link 118 and the arm 120 (Figs. 1 and 4), so that the drive to the master-sheet is silenced. When, however, the carriage reaches the end 15 of its return movement, a valve is automatically opened, so as to excite to action the pneumatic actuator 203, to effect an interruption of the drive for the carriage-return mechanism. This will also effect a return of the bar 116 to its normal position, 20 thereby permitting the gear 64 to drop into mesh with the gear 63, continuing the feed of the master sheet. The master sheet will thus be moved along to bring two new perforations into play, one corresponding to the 25 rotation of the platen so as to remove the work-sheet already on the platen, and the other corresponding to the picking up of a fresh sheet of paper by the sheet lifter 283. The first of these perforations excites the 30 actuator 242 to action, so that it thrusts forwardly the plunger 243 to rock the lever 240, which actuates the clutch-shifter 236 against the tension of the spring 237, to connect the shaft 228 in driven relation with the continuously-rotating sprocket 232. The shaft 35 228 on being driven, rotates, through the connecting gearing, the platen 7 any predetermined amount, so as to remove, or at least partially remove, the completely written 40 work-sheet from the platen, to deposit it in the basket or receptacle in front of the type-writer. The extent of this rotation is determined by the distance traveled by the valve 256 before it comes into engagement with 45 the stop or trip 261, which has been previously adjusted for a rotation of the platen corresponding to any desired number of line spaces. The opening of the valve 256 excites the same actuator 203 to action, which 50 was excited to action at the end of the carriage return, so that the driving connection to the feeding mechanism for the master sheet, which was also interrupted at the starting of the platen into rotation, will be 55 once more completed.

As stated above, the feed to the master sheet is interrupted while the platen is being rotated through the rotation of the shaft 228. Hence, the perforation which caused 60 the collapse of the bellows 242, stops in register with its aperture and remains there until the rotation of the platen has been stopped by the actuation of the valve 270.

When these acts have been accomplished 65 and the rotation of the shaft 228 ceases, the

pneumatic actuator 203 not only interrupts the drive to the shaft 228 but also permits the feeding mechanism of the master sheet 70 42 to come once more into action thereby feeding the perforation which was in register with their corresponding aperture, to pass by the same.

As the master sheet feeds along, it brings a second platen-rotating perforation into 75 register with its aperture, so that the shaft 228 is once more rotated to finish the discharge of the previously written work-sheet if it has not already been entirely fed from the platen, and advance the new work-sheet 80 around the platen 7, to bring the desired line to be written on to the printing point. The valve 256 once more silences the drive to the platen 7 and enables the further feeding of the master sheet 42.

A change may be made from the master 85 sheet to the master card, and vice versa, at any point in the writing of the letter. To accomplish these objects, it is merely necessary to place the "control change" perforations at the proper points. 90

Variations may be resorted to within the scope of the invention, and portions of the improvements may be used without others.

Having thus described my invention, I claim:

1. The combination with a platen, of a train of driving connections for rotating said platen, having a normally silent element therein, a source of power, a clutch connecting said element in driven relation with said source of power, a shifter for said clutch, a spring normally holding said clutch open, and an automatic actuator for operating said shifter to close said clutch. 95

2. The combination with a platen, of a 100 train of driving connections for rotating said platen, having a normally silent element therein, a source of power, a clutch connecting said silent element in driven relation with said source of power to actuate said 105 train of driving connections, said clutch being normally open, and a pneumatic actuator for closing said clutch. 110

3. The combination with a platen, of a 115 source of power, a normally interrupted train of driving connections extending between said source of power and said platen, means for completing said train of driving connections to enable said platen to be rotated by said source of power, and means for interrupting 120 said train of driving connections after a predetermined rotation of said platen by said source of power. 125

4. The combination with a platen, of a source of power, a normally interrupted train of driving connections extending between said source of power and said platen, means for completing said train of driving connections to enable said platen to be rotated by said 130 source of power, and means for interrupt-

ing said train of driving connections after a predetermined rotation of said platen by said source of power, said last mentioned means being adjustable to vary the rotation of said platen by said source of power.

5. The combination with a platen, of a source of power for rotating said platen, a normally interrupted train of driving connections between said source of power and said platen, a master control set for completing said train of driving connections to enable the rotation of said platen by said source of power, and automatic means for interrupting said train of driving connections after a predetermined rotation of said platen.

6. The combination with a platen, of a line-space mechanism for said platen, a master control set for governing the action of said line-space mechanism, and additional means for rotating said platen independently of said line-space mechanism, also governed from said master control set.

7. The combination with a platen, of driving means for rotating said platen, controlling means for governing the rotation of said platen having a traveling movement accord- 90
ant with the desired rotation of said platen, and a trip for operating said controlling means at the end of a predetermined traveling movement thereof, said trip being adjustable to vary the traveling movement of said controlling means and hence the rotary movement of said platen.

8. The combination with a platen, of driving means for rotating said platen, controlling means for governing the extent of rotation of said platen by said driving means, traversing mechanism for said controlling means actuated from said driving means to cause a lengthwise traveling movement of said controlling means coördinate with the desired rotation of said platen, and means located in the line of travel for tripping said controlling means at the end of the desired rotation of said platen.

9. The combination with a platen, of driving means for said platen, controlling means for governing the extent of drive of said platen by said driving means, said controlling means having a longitudinal travel coördinate with the desired rotation of said platen, and means for varying the extent of travel of said controlling means to correspond with the desired extent of rotation of said platen.

10. The combination with a platen, of driving means for said platen, automatic mechanism for starting said driving means into action, and automatic controlling means for interrupting said driving means after a predetermined rotation of said platen.

11. The combination with a platen, of driving means for said platen, controlling means for governing the extent of rotation of

said platen by said driving means, a screw driven by said driving means, a member carried by said controlling means engaging said screw at the initiation of a driving action of said platen, to traverse said controlling means, and tripping means brought into play after a predetermined traveling movement of said controlling means to enable the disconnection by said controlling means of said driving means from active driving relation 75 with said platen.

12. The combination with a platen, of a driving connection for said platen, a clutch for bringing said driving connection into effective action, a shifter for said clutch, 80 actuating mechanism for said shifter, controlling means for governing the period of activity of said actuating mechanism, said controlling means including a traveling element, a screw driven by said driving connection for traversing said traveling element, a member carried by said traveling element, brought into engagement with said screw at the connection of said clutch, and a trip for actuating said controlling means after a pre- 90 determined travel of said traveling element.

13. The combination with a platen, of a driving connection for rotating said platen, said driving connection being normally interrupted, means for completing said driving connection, controlling means for governing the period of activity of said driving connection, said controlling means including a traveling element, a swinging frame for said traveling element, a screw traversing 100 said traveling element, said swinging frame bringing said screw and said traveling element into coöperative relation, and a trip for operating said traveling element after a predetermined movement corresponding to 105 a desired rotation of said platen.

14. The combination with a platen, of driving mechanism for said platen, a pneumatic actuator for controlling the period of activity of said driving mechanism, a valve 110 for controlling said pneumatic actuator, a carriage for said valve, traversing means for said carriage, and a trip for opening said valve after a predetermined movement of said carriage and said valve.

15. The combination with a platen, of driving means for rotating said platen, a pneumatic actuator for controlling the period of operation of said driving means, a valve for controlling said pneumatic actuator, a screw driven by said driving means, mechanism for swinging said valve into coöperative relation with said screw, whereby said valve may be traversed by said screw, and a trip for opening said valve to excite said 120 pneumatic actuator to operation after a predetermined travel of said valve.

16. The combination with a platen, of driving means for rotating said platen, controlling means for governing the state of ro- 130

- tation of said platen, traversing means for said controlling means, a lever for concomitantly completing said driving means to enable the rotation of said platen and connecting said controlling means in traveling relation with said traversing means, and means operated by said controlling means for concomitantly interrupting said driving means and enabling the return of said controlling means to its normal position. 10
17. The combination with a platen, of driving means for said platen, controlling means for governing the extent of rotation of said platen by said driving means, said controlling means having a traveling element, means for traversing said element, and means for returning said traveling element to its normal position after it has completed its function. 15
18. The combination with a platen, of an axle for said platen, a sprocket on said axle, a chain for driving said sprocket, a sprocket for driving said chain, a clutch for enabling the drive of said last-mentioned sprocket, a shifter for said clutch, a lever for actuating said shifter, and an actuator for manipulating said lever. 20
19. The combination with a platen, of a normally interrupted train of gearing to said platen, shifting means for completing said train of gearing, including a lever, an actuator for operating said lever, and a plunger operated by said actuator and engaging said lever to rock the same. 25
20. The combination with a platen, of a normally interrupted train of gearing to said platen, shifting means for completing said train of gearing, including a lever, an actuator for operating said lever, a plunger operated by said actuator and engaging said lever to rock the same. 30
- 40
- lever to rock the same, and means for disengaging said plunger from said lever after a predetermined rotation of said platen. 45
21. The combination with a platen, of a normally interrupted train of gearing to said platen, shifting means for completing said train of gearing, including a lever, an actuator for rocking said lever, a plunger operated by said actuator and engaging said lever to shift the same, and an actuator brought into play after a predetermined rotation of said platen for disengaging said plunger from said lever to enable the interruption of said train of gearing. 50
22. The combination with a platen, of driving means for said platen, a valve controlling the action of said driving means, traversing means for said valve, means disconnecting said valve from said traversing means, and a spring for returning said valve to its normal position. 55
23. The combination with a platen, of pneumatically actuated line-spacing means for said platen, and pneumatically controlled driving means for rotating said platen. 60
24. The combination with a platen, of driving means for rotating said platen, and controlling means for said driving means located at a point distant from said platen for determining the extent of rotation of said platen, said controlling means including a longitudinal traveling element and a trip for the same at the end of travel thereof, thereby determining the extent of rotation of said platen. 70
